United States Patent Office.

ROBERT L. REAT, OF CHARLESTON, ILLINOIS.

Design No. 4,286, dated August 9, 1870.

DESIGN FOR NECK-YOKE RING AND SLIDE.

The Schedule referred to in these Letters Patent and making part of the same.

To all whom it may concern:

Be it known that I, ROBERT L. REAT, of Charleston, in the county of Coles and State of Illinois, have invented a new and original Design for Neck-yoke Ring and Slide; and I do hereby declare that the following is a full, clear, and exact description thereof, which will enable others skilled in the art to make and use the same, reference being had to the accompanying drawing forming part of this specification.

Figure 1 represents a perspective view of my new design for neck-yoke ring.

Figure 2 is a transvere section of the same.

Similar letters of reference indicate corresponding parts.

This invention relates to a new design for the rings and slides of neck-yokes.

The "ring" A is made either entirely rounded or

with sharp corners, as shown in fig. 1, and has an eye, a, at one end, for the reception of the screw or rivet by which it is secured to the neck-yoke.

The "slide" B is, by a pin, b, pivoted to the ring, as shown, and is made in form of a segment, with projecting legs d at the sides, and with an ogee-shaped back or upper face, c.

The slide is shown in figs. 1 and 2 as having the breast-strap applied, and in fig. 1 the ring is shown secured to a section of a neck-yoke, the latter being indicated in dotted lines.

I claim as my invention—

The design for the rings and slides of neck-yokes, as shown.

ROBERT L. REAT.
